UNITED STATES PATENT OFFICE.

ROY E. WILT, OF ARCANUM, OHIO.

EXCAVATING MACHINE.

Application filed April 5, 1921. Serial No. 458,673.

To all whom it may concern:

Be it known that I, Roy E. WILT, a citizen of the United States, residing at Arcanum, in the county of Darke, State of Ohio, have invented a new and useful Excavating Machine; and I do hereby declare the following to be a full, clear, and exact description of the invention, such as will enable others skilled in the art to which it 5 appertains to make and use the same.

The invention relates to excavating machines of the pivoted boom type, and has for its object to provide a machine of this character wherein a traveler is mounted in the boom, which traveler is longitudinally movable and controlled by a cable, and is provided with a downwardly extending digging element, the angle of which digging element is controllable from a point on the frame of 10 the machine through the pivotal point of the mast and the boom.

A further object is to provide an excavating machine of the boom type, on which boom a traveler is movable and provided 15 with a digging element underslung in relation to the boom, said boom being universally connected to the mast of the machine, thereby allowing the digging element to assume a horizontal position at all times 20 for insuring a horizontal digging operation. The horizontal digging operation is particularly advantageous in road building and repairing, wherein when it is desired to resurface a road, a thin cut may be removed 25 from the surface of the road of any desired thickness. Also to provide means controllable from the body of the machine for varying the angle of the digging element, and for inclining the digging element for 30 dumping purposes.

A further object is to provide a universal connection between the boom and mast, said connection comprising a U-shaped member pivoted horizontally to the mast 45 and adapted to move in a vertical plane, the outer end of said U-shaped member terminating in a boss, on which boss is pivotally mounted the rear end of the boom, said boom being so pivoted that it will pivot in 50 a vertical plane transversely. Also to provide a brake band cooperating with the rear end of the boom, for holding said boom against pivotal action if so desired. Also to provide means comprising gearing and 55 shafting for transmitting power upwardly through the lower pivotal point of the mast,

outwardly through the pivotal points of the boom and thence outwardly over shafting to a traveler which is cable controlled, and thence downwardly for controlling and manipulating the digging element.

A further object is to provide in combination with a boom of an excavating machine, a traveler movable on said boom, said traveler comprising spaced plates disposed on each side of the boom, a digging element pivotally mounted on downwardly extending rigid arms, a shaft having gears at its ends extending through the plates, oppositely extending arms carried by the ends of said shaft and having link connections with the digging element in such a manner as to form a parallel movement, a shaft extending through the plates and disposed above the boom, the ends of said last named shaft being provided with gears meshing with the first mentioned gears and forming means for varying the angle of the digging element. Also to provide a longitudinally disposed shaft rotatably mounted in 80 bearings carried by the boom said longitudinally disposed shaft having a worm slidably mounted thereon, which worm meshes with a worm gear carried by the transversely disposed shaft located above 85 the boom, and by means of which longitudinally disposed shaft the angle of the digging element may be varied during the longitudinal movement of the traveler and the digging element.

With the above and other objects in view the invention resides in the combination and arrangement of parts as hereinafter set forth, shown in the drawings, described and claimed, it being understood that changes 90 in the precise embodiment of the invention may be made within the scope of what is claimed without departing from the spirit of the invention.

In the drawings:—

Figure 1 is a side elevation of the excavating machine.

Figure 2 is a horizontal sectional view taken on line 2—2 of Figure 1.

Figure 3 is a sectional view taken on line 105 3—3 of Figure 1, showing the boom and traveler in top plan.

Figure 4 is a vertical sectional view taken on line 4—4 of Figure 1.

Figure 5 is a horizontal sectional view 110 taken on line 5—5 of Figure 1.

Figure 6 is a detail perspective view of

the rear end of the boom, showing the brake band for locking the boom against pivotal action.

Figure 7 is a detail sectional view vertically through the lower end of the mast, showing the power shaft extending upwardly therethrough.

Referring to the drawings, the numeral 1 designates the platform of the machine, 10 which platform may be built up in any suitable manner. The platform 1 is supported on wheels 3, thereby allowing the machine as a whole to be moved from place to place as desired. Pivottally mounted in a bearing 4 15 of the platform 1 is the reduced portion 5 of the upwardly extending mast 6. The mast 6 is formed from spaced bars which are integrally joined at their upper ends and terminate in a reduced cylindrical portion 7 20 which has a bearing in the mast cap 8, the mast being adapted to be pivoted in its bearings 4 and the bearing of the cap 8. Secured to the mast 6 adjacent its lower end is a horizontally disposed turntable 9, 25 around which turntable a cable 10 extends, said cable extending rearwardly and over a drum 11, which drum is rotated from the main drive shaft 12 through the medium of the gears 13, shaft 14 and shiftable clutch 30 15, and by means of which clutch the direction of rotation of the drum 11 may be changed as desired. A brake 16 of the band type is utilized for cooperating with the drum 11 for holding the same against rotation after the mast has been rotated to the direction position. The main drive shaft 12 is driven by a conventional form of steam engine 17, which gets its source of power from a boiler 18, said engine and 40 boiler is on the platform 1, preferably adjacent its rear end, however it is to be understood that the controlling mechanism for the various cables may be of any construction and located any place desired on the 45 platform 1 and that the particular positioning of the various drums and the particular construction of said drums and controlling mechanism is primarily for the purposes of illustration, of controlling means for the 50 cables hereinafter set forth.

Extending transversely through the mast 6 is a shaft 19, to the outer ends of which shaft are pivotally connected the arms 20 of a U-shaped yoke 21. The end of the 55 U-shaped yoke 21 is provided with a cylindrical boss 22, which is disposed in the aperture 23 of the rear end 24 of the boom 25. The boom 25 is pivoted on the cylindrical boss 22 in such a manner that it will pivot 60 on its axis, and at a right angle to the pivotal movement of the yoke 21, therefore a universal pivotal action is obtained for the boom, the purpose of which will presently appear. However at times it is desirable to 65 lock the boom 25 against axial pivotal move-

ment and to accomplish this result the brake band 26 is provided which brake band is carried by a lug 27 on the yoke 21 and arches the upwardly extending segmentally shaped portion 28 of the rear end of the boom 25. To control the brake band 26, a lever 29 is provided, which lever is pivotally mounted as at 30 on the side of the yoke 21 and has its end pivotally connected at 31 to the band 26. It will be seen that when the lever 29 is rocked that the brake band 26 will be forced into or out of engagement with the segmentally shaped portion 28 for holding or releasing the boom 25. The pivoted lever 29 may be held in various positions by any of the notches of the rack bar 32 carried by the side of one of the arms 20 of the yoke 21.

Longitudinally movable on the boom 25 is a traveler 33, which traveler comprises 85 spaced plates 34 disposed to the outside of the sides of the boom 25, said plates being connected together by transversely disposed shafts 35, on which shafts are mounted flanged rollers 36, which rollers engage 90 the upper surfaces of the side bars of the boom 25 in such a manner that the traveler 33 may move longitudinally in either direction on the boom 25. Disposed beneath the side rails of the boom 25 and pivotally mounted on shafts 37 carried by the plates 34 are rollers 38, which rollers engage the underside of the boom and prevent tilting of the traveler as a whole during its longitudinal movement. It will be seen that the 100 traveler as a whole is roller supported and that it will easily move longitudinally on the boom during an excavating operation. Extending transversely through the plates 34 and disposed below the boom 25 is a shaft 105 39, which shaft is provided adjacent its ends with gears 40 which mesh with gears 41 carried by the ends of the shaft 42 which extends through the plates 34 at a point above the beam 25. It will be seen that when 110 the shaft 42 is rotated that the gears 40 will also rotate and consequently the shaft 39 located beneath the boom will be rocked in its bearings through the medium of the gears 40. Secured to the ends of the shaft 115 39 are bars 41^a, the arms of which extend in opposite direction and have pivoted to their ends as at 42 downwardly extending links 43, the lower ends of which are pivotally connected as at 44 to a digging shovel 45. The pivotal points 44 and the pivotal points 120 42 are of equal distance with relation to each other thereby forming a parallel movement which will maintain the bars 41^a in parallel relation to the shovel 45 at all times, thereby allowing positioning of the shovel 125 in a horizontal plane for taking a small cut off the road, and also allowing the forward cutting edge of the shovel to be positioned for a digging operation or in a position 130

where it will cut its way from the ground. The shovel 45 is pivotally mounted at 46 on downwardly extending rigid arms 47 of the traveler, and on which arms the 5 shovel pivots at all times. Rotatably mounted in bearings 48 of brackets extending upwardly from the boom 25 is a shaft 49, on which shaft is slidably keyed a worm 50. The worm 50 meshes with a worm gear 51 carried by the shaft 42. It will be seen that when the shaft 49 rotates that the worm 50 will also rotate and rotate the shaft 42 through the worm gear 51. When this action takes place the arms of the bars 41^a are rocked, and consequently the shovel is tilted according to the rotation of the shaft 49 and the digging shovel controlled in its 10 pivotal movement in a longitudinal vertical plane. By slidably keying the worm 50 on the shaft 49 it will be seen that as the traveler 33 moves longitudinally in either direction that the worm 50 will also move longitudinally on the shaft 49 and will at all times be in a position where it will 15 operate the digging mechanism.

Connected to the shaft 37 is a cable 51^a, which cable extends outwardly and over a pulley 52 and thence upwardly and rearwardly over a pulley 53 and has its free 20 end 54 extending around a drum 55, said cable then extends upwardly as at 56 and over a pulley 57 carried by the mast 6, thence downwardly over a guide pulley 58 and has its end connected as at 59 to a pivoted bail 25 60 carried by the shovel 45. It will be seen that by throwing the clutch 61 into driving engagement with the drum 55 that the drum 55 may be rotated in either direction through the medium of the bevel gear connections 62 30 with the drive shaft 12. During an excavating operation the shovel is pulled in the direction of the machine by the cable end connected to the bail 60 and the traveler as a whole is moved outwardly in the direction of the end of the boom by the other end of the cable which passes over the pulley 52 and is connected as at 51 to the shaft 35. It will be seen that the traveler and the digger is under control of the operator at all times during the digging operation and that a thin cut or a heavy cut may be taken from the road bed as desired. Also the machine may be used for ditching purposes.

55 The boom 25 is lowered and raised during a digging operation through the medium of the block and fall 63, the lead end of the rope of which is designated by the numeral 64 and extends over a pulley 65 carried by the mast 6, said lead end extending downwardly and passes around the clutch controlled drum 65^a which is also operated from the main drive shaft 12 through the medium of the bevel gears 66. During a 60 digging and hoisting operation the boom 25 65

may be raised or lowered as desired for properly positioning the shovel 25 in relation to the ground. The boom may also be raised during the dumping operation, which dumping operation is accomplished by extreme tilting of the shovel 45.

The inner end of the shaft 49 is provided with a gear 67, which gear is located adjacent the segmental portion 28 of the end 24 of the boom 25. Gear 67 meshes with a gear 68 carried by a shaft 69, which shaft is rotatably mounted in a bearing 70 of the cylindrical extension 22 of the yoke 21. It will be seen that the shaft 69 is axially disposed in relation to the pivotal point of the boom 25 and consequently the gear 67 will move on the proper arc during the pivotal action of the boom thereby preventing binding of the gears 67 and 68 during the pivotal action of the boom. Shaft 69 extends rearwardly and is provided with a bevel gear 71, which meshes with a bevel gear 72 carried by the shaft 19. Mounted on the platform 1 are brackets 73, and in bearings of which the pintles of the sprockets 74 are rotatably mounted. Disposed beneath the platform 1 and preferably in alignment with the mast 6 is a transversely disposed shaft 75 which is provided with a sprocket 76 and around said sprocket 76 and the sprocket 74, a chain 77 extends through the medium of said chain the shaft 75 is rotated. However it is to be understood that the chain may be eliminated and shaft driving mechanism substituted therefor. Ex- 90

tending vertically through the reduced portion 5 of the mast 6 is a vertically disposed shaft 78. The upper end of the shaft 78 is provided with a bevel gear 79 which meshes with the bevel gear 72, while the lower end of the shaft 78 is provided with a bevel gear 80, which meshes with a bevel gear 81 carried by the transversely disposed shaft 75. It will be seen that when the sprocket 74 is rotated that shaft 75, vertically disposed shaft 78, transversely disposed shaft 19, shaft 69 and 49 will be rotated thereby allowing the operator to control the digging element in its movement from a point adjacent the rear end of the platform 1 in such a manner that the operation is positive and substantially by mechanism wherein the power is transmitted through the pivotal connections of the mast with the platform and the boom with the mast. One of the pintles of the sprocket 74 is provided with a beveled gear 82, with which beveled gear the gears 83 of a shiftable clutch member 74 may be meshed whereby a rotation in either direction may be imparted to the shaft 75 for reversing the direction of rotation of the shaft 49. The clutch member 84 is slidably keyed on a shaft 85, which shaft has a beveled gear connection 86 with the main drive shaft 12. 130

The invention having been set forth what is claimed as new and useful is:—

1. In a device of the class described, the combination with a boom, of a traveler longitudinally movable on said boom, said traveler having a shaft rotatably mounted therein at a point above the boom and a shaft rotatably mounted therein at a point below the boom, gear connections between said shafts, downwardly extending brackets carried by the traveler, a digging shovel pivotally mounted in the downwardly extending brackets, parallel link connections between the shaft carried by the traveler below the boom and the shovel, a gear carried by the upper shaft substantially centrally thereof, a shaft disposed above the upper shaft and at right angles thereto, a worm slidably keyed on said shaft disposed above the upper shaft and meshing with the centrally disposed gear of the upper shaft and forming means for operating the gear connections between the upper and lower shafts and varying the position of the digging shovel through the parallel connections.

2. The combination with a traveler mounted on a boom of an excavating machine, of a digging shovel carried by said traveler, downwardly extending arms carried by the traveler, said digging shovel being pivotally mounted on the downwardly extending arms, mechanism carried by the traveler whereby the digging shovel may be controlled in its pivotal movement in a longitudinal vertical plane, and link connections between the digging shovel controlling mechanism and the digging shovel.

3. In a device of the class described, the combination with a traveler mounted on a boom, of a digging shovel carried by said traveler, downwardly extending arms carried by the traveler, said digging shovel being pivotally mounted on the downwardly extending arms, a shaft extending through the traveler and disposed above the boom, a shaft extending through the traveler and disposed below the boom gear connections between said shafts, oppositely extending arms carried by the ends of the shaft below the boom, parallel link connections between the ends of the oppositely extending arms and the ends of the digging shovel and shaft and gear connections whereby said parallel link connections may be controlled from a remote point and the digging shovel pivotally moved in a longitudinal vertical plane.

4. The combination with an excavating machine comprising a boom carried by a mast, of a traveler carried digging element longitudinally movable on the boom, said boom comprising two aligned sections, a pivotal connection between the boom sections whereby one section may move axially independently of the other section, the digging

element of the traveler being disposed below the boom and on the pivoted section thereof, said pivotal connection of the boom sections forming means whereby the digging element will maintain its relative relation to the ground.

5. The combination with an excavating machine comprising a mast, a boom formed from aligned sections extending outwardly from the mast, a traveler movable on the boom, a downwardly extending digging element carried by the traveler and disposed beneath the boom, of a pivotal connection between the boom sections and spaced from the ends of the boom and forming means whereby said digging element will maintain its relative vertical relation to the boom at all times by axial movement of the outer boom section.

6. The combination with an excavating machine comprising a mast, a boom pivoted to the mast and movable in a vertical plane, said boom being formed from pivotally connected aligned sections, said boom having a traveler mounted thereon, a downwardly extending digging element carried by the traveler and disposed below the boom, said pivotal connection in the boom being spaced from its ends, means carried by the traveler for controlling the digging element and means for controlling the last named controlling means from a remote point.

7. The combination with an excavating machine having a mast, a boom pivoted to said mast and movable in a vertical plane, said boom having a traveler mounted thereon, a digging element carried by the traveler and located below the boom, said boom being formed from aligned sections, of a pivotal connection between the boom sections and forming means whereby the weight of the digging element will cause pivotal movement of the outer boom section axially on which the digging element is disposed and the digging element maintained in the same vertical plane during its operation, controllable mechanism carried by the traveler for controlling the digging element and means whereby power is transmitted to the controllable mechanism through the pivotal connection of the boom sections.

8. The combination with an excavating machine having a vertically disposed pivoted mast, a boom pivoted to the mast and movable in a vertical plane, said boom being formed from aligned sections, a traveler mounted on the boom and movable on the outer section, a digging element carried by the traveler and longitudinally movable therewith and extending downwardly below the boom, of a pivotal connection between the boom sections and forming means whereby the digging element will maintain a vertical position by gravity by an axial movement of the outer boom section, cable means for mov-

ing the traveler longitudinally in either direction, controlling mechanism carried by the traveler for controlling the digging element carried thereby, shaft and gear connections whereby power may be imparted to the digger controlling mechanism of the traveler from the body of the machine, said gear and shaft connections transmitting power through the pivotal points of the pivoted 10 mast and the pivotal connection of the boom

to the traveler when said traveler is in various longitudinal positions.

In testimony whereof I have signed my name to this specification in the presence of two subscribing witnesses.

ROY E. WILT.
